ABRADING MACHINE

Arthur N. Emmons, Syracuse, N. Y., assignor to
The Porter-Cable Machine Company, Syracuse,
N. Y., a corporation of New York

Application February 6, 1933, Serial No. 655,374

9 Claims. (Cl. 51—176)

This invention relates to abrading machines which are pushed over the floor, or other surface, to be finished, and has for its object a particularly simple and economical, and compact construction, or assembly of the supporting, or main frame elements, of an abrading machine, also the arrangement of a carriage which supports the abrading drum, and the suction fan for collecting the dust from the drum and discharging it into a receptacle, the motor for actuating the drum and the fan, and the supporting of the drum from the motor housing.

The invention consists in the novel features and in the combinations and constructions hereinafter set forth and claimed.

In describing this invention, reference is had to the accompanying drawings in which like characters designate corresponding parts in all the views.

20 Figure 1 is a side elevation of an abrading machine embodying my invention.

Figure 2 is a sectional view on line 2—2, Figure 1.

Figure 3 is a plan view of the carriage.

25 Figure 4 is a rear elevation of the carriage, partly in section, showing the arrangement of the fan in the fan compartment or housing of the carriage.

Figure 5 is a perspective view of the truck. Figure 6 is a perspective view of the bracket, or fork head, which is secured to the motor housing.

This abrading machine includes a carriage pivotally mounted on a truck on a transverse horizontal axis to tilt slightly to raise and lower the drum carried at the front end of the carriage and thus, vary the pressure of the drum against the surface, or floor, being treated, or finished, said carriage being a unitary piece, as a hollow skeleton casting provided with internal partitions which provide a housing for a centrifugal fan, and a forwardly extending inlet for the fan housing opening through the front end of the carriage adjacent the rear of the drum, the inlet passage opening centrally into the fan housing, and an upwardly extending tangential outlet passage through the top of the carriage for connection to an exhaust pipe delivering into a suitable dust receptacle, a motor having its casing rigidly mounted on the top of this unitary carriage with its axis extending transversely, and motion transmitting means between the rotor of the motor and the drum, and between the rotor of the motor and the fan in the housing.

55 I designates a truck, or chassis, having sup-

porting wheels 2 and 3 at its front and rear ends. This chassis, as shown in Figure 5, is in the general form of a Y with the leg 4 of the Y formation extending upward at a rearwardly inclined angle, and to which a handle 5 is secured, and the branches of the Y formation constitute sills on which the carriage is supported, or pivoted. The front wheels 2 are supported at the front ends of the branches, or sills, and the rear wheel is preferably a caster wheel mounted in a bracket 6 extending rearwardly from the leg 4.

1 designates the carriage which is a hollow or skeleton block casing pivotally mounted at 8 on the truck 1, or the side sills thereof, the pivot 8 being located in the rear of and near the front wheels 2, and is located as low as possible, or near the horizontal plane of the axis of the wheels 2. The carriage 7 is formed with bearings 10 mounted on axles or pivots, these being the ends of a shaft or pivot pin 8 extending through the intermediate or hub portion 8a of the Y shaped truck 1. The carriage 7 is cast with partitions 11 and 12 therein which provide a fan compartment 13 and an air inlet 14, the compartment being located at one side of the rear end of the casting about midway between the wheels 2, 3, and the inlet extending forwardly through the front end of the carriage and opening at its rear end into the fan compartment 13 through a central inlet 15. The fan compartment is open at its outer side on one side of the machine and is closed by a plate 16 secured in position as by screws 17, in which the plate is mounted, a spindle 18 on which a centrifugal fan rotor 19 is mounted within the compartment 13. The plate 16 is provided with a hub in which the spindle is mounted, and suitable anti-friction bearings 20 are interposed between the hub and the spindle 18. The casting is also provided with a substantially flat top, and the fan compartment is provided with an outlet 21 opening through the top of the carriage at one corner thereof.

22 is an abrading drum mounted on an axle 23 supported by a fork 24 which is carried by a bracket or head 25 rigidly secured to the housing 26 of the motor, to be presently described, the bracket or head 25 overhanging the front end of the carriage 7 so that the drum runs close to the front end of the carriage and the front end of the air intake passage 14. The fork 24 is connected to suitable spring means located in the hubs 25^a on the bracket or head 25, to spring press the drum and more or less yieldingly support it, and the tension of the spring means is adjusted in any suitable manner, as by nuts 27. The par-

ticular manner of supporting the forks 24 in the hubs 25^a per se, forms no part of this invention, but the supporting of the head or bracket 25 on the motor housing 26, as a unit therewith, is one of the features of this invention.

The motor is mounted in the housing or casing 26, and this casing is secured on the top of the carriage 7 as by screws 28 which thread into openings 29 in the top of the carriage 7, and the motor 26 is located relatively to the pivot 8 of the carriage to balance or counterbalance the weight thereof, and the weight of the drum 22 during the tilting of the carriage, as will be presently described.

The machine thus has a main frame which consists of three main elements, the truck or chassis 1, the carriage 7, pivoted to the truck or chassis 1, the housing or casing 26 of the motor and the bracket or plate 25 which is secured directly to the housing 26. This provides a particularly simple, compact, and economical frame for the machine which results in a compact structure consisting of a minimum number of parts which can be easily and economically assembled. This arrangement of the chassis 1, carriage 7, housing 26 for the motor and bracket or plate 25 with particular reference to the mounting of the bracket or plate 25, which supports, for the abrading drum, on the motor housing, constitutes one of the features of this invention.

A suitable entrance scoop, or dust collector 30 is secured to the front end of the carriage 7, and extends under the drum 22 to collect the dust formed by the drum, and deflect it into the inlet passage 14 of the fan. The forks 24 also have forwardly extending arms 31 carrying a buffer 32 extending transversely of the front portion of the roller and to which is secured a shield 33. The motion of the rotor of the motor is transferred to the drum 22 by suitable means, here shown as a belt 34 running over a pulley 35 at one end of the drum 22, and over a pulley 36 on one end of the motor shaft 37. Also, suitable motion transmitting means connect the rotor or shaft of the motor with the fan 19, this being shown as a belt 40 running over a pulley 41 on the motor shaft, and a pulley 42 on the spindle 18 of the fan. The belts are enclosed in suitable casings or guards 43, 44. 45 is an outlet pipe leading from the fan compartment 13 and discharging into a suitable dust receptacle 46 carried at the rear of the machine.

The carriage 7 is tilted about its pivot 8 by a suitable rock arm 47 pivoted at 48 to the handle 5 near the upper end thereof, and motion transmitting means, as a link 50, connecting a rock arm 51 on the handle and the carriage, it being pivoted to the carriage at 52, these connections including certain spring adjusting means forming no part of this invention.

55 is a support for the cable enclosing the service wires for the electric motor, this extending upwardly and being for the purpose of holding the wire high enough so that it will not lie on the floor in the path of the drum 22. This arm 55 is pivoted at 56 to swing transversely to different angles in order to most advantageously arrange the cable so as not to interfere with the drum 22.

70 57 is a switch by means of which the current to the motor is turned on and off, the switch being mounted on a terminal box 58, to the terminal of which the service wires in the cable are connected, the box being mounted on, or integral with, the motor housing.

Owing to the carriage construction and the mounting of the motor and forks for the drum, the machine is particularly compact in construction, and economical to manufacture, as the carriage with the fan therein is assembled as one unit, the motor and the drum as another unit, and the latter unit assembled on the carriage, and there are no mechanical connections to be made between the mechanism of the motor and the carriage, other than the belts 34 and 40.

What I claim is:

1. In an abrading machine of the type described, the combination of a truck, a carriage pivoted on a transverse horizontal axis to the truck, an abrading drum projecting in front of the carriage, driving mechanism for the drum including an electric motor having its housing mounted on and rigid with the carriage, motion transmitting means between the rotor of the motor and the drum, a support for the abrading drum secured to and carried by said motor housing, and means for tilting the carriage relative to the truck for raising and lowering the drum.

2. In an abrading machine of the type described, the combination of a truck, a carriage pivoted on a horizontal axis to the truck, an abrading drum projecting in front of the carriage, a motor mounted on the carriage and having a housing rigid therewith, a support for the drum including a bracket, and means for detachably securing the bracket to the motor housing, motion transmitting means between the motor and the drum, and means for tilting the carriage on its pivot for raising and lowering the drum.

3. In an abrading machine of the class described, the combination of an abrading drum, a frame for carrying it including four elements, one element being a truck, the second element a carriage pivoted on the truck on a transverse horizontal axis, the third element being a motor housing mounted on the carriage and rigidly secured thereto, and the fourth element, a support for the drum secured to the front end of the motor housing, a motor mounted in the housing, motion transmitting means between the motor and the drum, and means for tilting the carriage about its horizontal axis to raise and lower it.

4. In an abrading machine of the type described, the combination of a truck frame having front and rear wheels, a carriage pivotally mounted on a transverse horizontal axis on the truck frame between the front and rear wheels, said carriage being an integral unitary piece formed with a fan casing between the lateral sides thereof and a forwardly extending inlet opening through the front end of the carriage, means supported by the carriage for supporting an abrading drum in front of and adjacent the front end of the carriage and the front end of the inlet of the fan housing, a motor including a casing rigidly mounted on the carriage, motion transmitting means between the rotor of the motor and the drum, a fan mounted in the fan housing, and motion transmitting means between the rotor of the motor and the fan, and means for tilting the carriage and parts carried thereby relatively to the truck.

5. In an abrading machine of the type described, the combination of a truck frame Y shaped in general form with the branches of the Y formation arranged in substantially horizontal position and extending forward and the leg of the Y formation extending upward at an inclined angle, wheels for running on a surface mounted at the front ends of the branches of the Y, and

5 a third wheel supporting the leg of the Y, a carriage pivoted to the truck between the front and rear wheels thereof, a motor mounted on the carriage, a drum supported on the carriage and located in front of the front end thereof and in front of the front wheels of the truck, motion transmitting means between the motor and the drum, a handle mounted on the leg of the Y formation, and means for tilting the carriage relative to the truck.

10 6. In an abrading machine of the type described, the combination of a truck frame Y shaped in general form with the branches of the Y formation arranged in substantially horizontal 15 position and extending forward, and the leg of the Y formation extending upward at an inclined angle, wheels for running on a surface mounted at the front ends of the branches of the Y, and a third wheel supporting the leg of the Y, a carriage pivoted between the legs of the Y, said carriage being an integral hollow casting formed with a partition providing a fan housing, an air inlet opening through the front end of the carriage and an outlet, a motor mounted on the top 20 of the carriage, an abrading drum, a fork carrying the same and supported from the front of the carriage, said drum being located in front of and adjacent the front end of the carriage and the air inlet, a fan in the fan compartment, motion transmitting means between the rotor of the 25 motor and the drum, and the fan, a handle carried by the leg of the Y formation and means for tilting the carriage and parts carried thereby as a unit relative to the truck.

30 7. In an abrading machine of the type described, the combination of a truck member having wheels for running on the surface being fin- 35

ished, a carriage mounted on the truck, an abrading drum projecting in front of the carriage, driving mechanism for the drum including an electric motor having its housing mounted on and rigid with the carriage, a support for the abrading drum secured to and carried by said motor housing, means operable to effect movement of the front portion of the carriage toward and from the wheels of the truck member.

5 8. In an abrading machine of the type described, the combination of a carriage, an electric motor having its housing mounted on and rigid with the carriage, and its rotor shaft extending transversely of the carriage and having one side of the motor housing extending across 10 the front edge of the carriage, a bracket extending across the forward side of the motor housing and being detachably secured thereto, means carried by the bracket for supporting the abrading drum, motion transmitting means between 15 the motor shaft and the drum, and means for tilting the carriage relative to the truck.

15 9. In an abrading machine of the type described, the combination of a truck frame Y shaped in general form, wheels for running on 20 a surface mounted at the ends of the branches of the Y, and a third wheel for supporting the leg of the Y, a carriage pivoted to the truck on a transverse pivot arranged adjacent the branches of the Y, a motor mounted on the carriage, an abrading drum supported on the carriage and located in front of the front end thereof, and in front of the front wheels of the truck, motion transmitting means between the motor 25 and the abrading drum, and means for tilting the carriage relative to the truck.

30 ARTHUR N. EMMONS.
